TRIMMING ATTACHMENT FOR SEWING MACHINES

Morris Feil, New York, N. Y.

Application September 10, 1937, Serial No. 163,163

1 Claim. (Cl. 112—139)

My present invention relates to attachments for sewing machines, and particularly to the type adapted for guiding a series of tapes to be simultaneously sewn.

5 The principal object of this invention is to provide a novel and improved attachment for sewing machines, to guide a series of differently colored tapes, superimposed longitudinally one on the other to be sewn simultaneously to form a decorative trimming.

Another object hereof is to provide a novel and improved attachment of the character described for guiding a series of differently colored tapes in longitudinal superimposed relation, the margins of each successive tape to lie exposed beyond the margins of each preceding tape, and whereby all tapes are simultaneously sewn onto a fabric to be trimmed thereby, in a single operation.

A further object hereof is to provide a novel 20 and improved device of the class mentioned which is cheap to manufacture, simple to use and which provides economy in the performance of the work to be accomplished.

Other objects will become manifest as this disclosure proceeds.

In the accompanying drawing, forming part of this application, similar characters of reference indicate corresponding parts in all the views.

Fig. 1 is a perspective view showing an attachment adapted for a multi-needle sewing machine which follows the teachings of my present invention.

Fig. 2 is a section taken at line 2—2 in Fig. 1.

Fig. 3 is a diagrammatic representation in side view, showing the manner in which my present invention is used.

Fig. 4 is a similar diagrammatic representation in front view.

Fig. 5 shows character of the work accomplished with my present invention, namely, a trimming done in one operation which heretofore required many single runs.

In the drawing, the numeral 15 designates generally a presser foot for a multi-needle sewing machine 16, the plate 17 of which foot is provided with the apertures, collectively designated by the numeral 18, for passage of the needles of said machine to their respective shuttles. In front of said apertures 18, and 45 transverse the direction of motion of material sewn by the machine 16, the plate 17 of said foot 15 is provided with a series of substantially parallel slots 19, 20 and 21 for the respective passage and guidance therethrough of the differently 50 colored tapes 22, 23 and 24 unwinding from off

the rolls 25, 26 and 27 respectively. The size of these slots is greater as their position is further away from the foot mounting means indicated generally by the numeral 28, which is of any ordinary construction for attachment to the 5 shank 29, and the extremities of any of these slots, lie within the extremities of the next larger slot. Also the extremities of each of said slots extend beyond different pairs of needles, so that in particular, the middle pair of needles 30 10 and 31, passing through the needle holes 33 and 34, would sew the longitudinal edges of tape 22 and all material beneath said tape, and the pair of needles 35 and 36, which have the first pair of needles mentioned intermediate them, would pass thru needle holes 37 and 38, and would sew the longitudinal edges of tape 23 and all material beneath said tape, and so on, depending upon the number of tapes, which may be two or more, to be sewn on to the material 39, as a trimming 20 for the latter. It is evident that such trimming would have the appearance as is illustrated in Fig. 5, and of course is accomplished in a single operation. When any single length of trimming is complete along the material 39, the tapes 22, 23 25 and 24 are simultaneously severed by a single shears cut behind the presser foot 15, whereby a new run may be commenced without any further manipulation or setting of the trimming tapes until their respective rolls are consumed. It is 30 evident that a single line of stitches 40 would be sufficient to accomplish the assembly, in which event, a single needle machine need be used. Of course, in such instance, to be a practical trimming, the difference in widths of the several tapes 35 should be small. When such difference is appreciable, it is preferable that the longitudinal edges of each tape be sewn as shown in Fig. 5.

This invention is capable of numerous forms and various applications without departing from 40 the essential features herein disclosed. It is therefore intended and desired that the specific embodiments shown herein shall be deemed illustrative and not restrictive, and that the patent shall cover whatever features of patentable novelty exist in the invention disclosed; reference being had to the following claim rather than to the specific description herein to indicate the scope of this invention.

50 I claim:

A trimming attachment for a multi-needle sewing machine, comprising a substantially horizontal plate member adapted to serve as the presser foot of the machine, and provided with a number of slots of different lengths adapted to 55

receive and guide therethrough tapes of respectively corresponding widths in superimposed relation whereby the longitudinal edges of any of the superimposed tapes lie intermediate the longitudinal edges of the tape immediately beneath it, and means to mount said plate onto the presser foot spindle of the sewing machine; said plate being also provided with a series of apertures to permit passage of the needles of the machine to

their respective shuttles; said apertures lying respectively in the path of travel of the respective tapes; each aperture being adjacent a longitudinal edge of one of the tapes, whereby said tapes may be sewn one on to the other along their longitudinal edges by a single run through the machine. 5

MORRIS FEIL.
